REENFORCED CONCRETE FENCE POST

Filed March 22, 1927

UNITED STATES PATENT OFFICE

ATLAS M. THOMPSON, OF GROTON, NEW YORK

REINFORCED CONCRETE FENCE POST

Application filed March 22, 1927. Serial No. 177,367.

This invention relates to improvements in reenforced concrete fence posts.

The primary object of the invention is to provide a concrete post which is reenforced in such a manner as to withstand all strains and stresses to which such a post is subjected, and particularly while in use as a fence post.

A further object of the invention is to provide a post of the above referred to character with novel supporting means for fence 10 runners or wires.

Other objects and advantages of the invention will be apparent as the description proceeds.

In the accompanying drawings forming a 15 part of this specification, and in which like numerals are employed to designate like parts throughout the same,

Figure 1 is a side elevational view, partly broken away, of one form of fence post embodying this invention,

Figure 2 is a side elevational view of a slightly modified form of post,

Figure 3 is a side elevational view of a 25 further modified form of post,

Figure 4 is a side elevational view of a still further modified form of post,

Figure 5 is a horizontal sectional view of the type of post shown in Fig. 3, and

Figure 6 is a horizontal sectional view of 30 another form of post which is a slight modification of the form shown in Fig. 3.

In the drawings, wherein for the purpose of illustration is shown a preferred embodiment of this invention, the numeral 10 designates the enlarged base portion of a fence post shown in Fig. 1. This base portion is substantially rectangular in side elevation and has projecting perpendicularly there-

40 from the substantially triangular portion 11 which merges into the extension 12. It is to be understood that the entire body portion of this post is formed from a suitable concrete or cement mixture and is reenforced by

45 the vertically extending spiral wires or rods 13 which are positioned relative to each other so as to properly reinforce a straight vertical portion of the entire post, the said portion being a true continuation of the extension

50 12. The remainder of the base portion 10

and the triangular part 11 are reenforced by the spaced and parallel reenforcing wires 14 which are of spiral formation. For the purpose of connecting the strands of wire forming a fence to the post, the triangular part 11 and the vertical extension 12 are formed with the tubular wire guides 15 embedded therein and extending horizontally, the wire fence being represented in its entirety by the reference character 16.

In the form shown in Figure 2, a slightly tapered post 17 is provided and is reenforced by the nested spiral strands of wire or rods 18. Connected to certain ones of the convolutions of these two reenforcing elements 18 are the laterally projecting fence wire tie elements 19 which are partially embedded in the concrete of the post body 17 and are formed into hook ends 19'.

In the form of fence post shown in Figures 3 and 5, a concrete body 20 is provided, of any desired shape. This body is reenforced by the criss-cross type of reenforcing rods 21 which are arranged with respect to each other so as to reinforce the entire body of the post. This type of post is formed with surface grooves 22 in one side thereof to receive the wire cable 23 forming the fence. It is considered that this post is especially adapted for guarding turns and ditches on highways. To secure the wire cables 23 to the post, the latter is formed with horizontally extending holes 24 which merge into the grooves 22 at one end and function to receive the tie elements 25. The wire cable 23 engaging end of each element 25 is hook shaped, as at 26, while the end projecting from the opposite end of the post hole 24 is threaded to receive the nut 27.

This same general type of post may be 50 formed as shown in Figure 6. This form shows a body portion 28 having a horizontally extending hole 29 which runs in the direction of the wire cable 30, the latter passing through the said hole. Of course, as many 55 holes 29 as desired may be formed in this type of post.

In the form of post shown in Figure 4, the body 20^a is reenforced in the same manner as the body 20, see Fig. 3, as by the zig-zag 100

type of reenforcing rods or wires 21^a. This post has secured thereto, as by the bolts 31, tie strips 32, formed of a suitable metal or wood, which are provided with bolt receiving apertures 33 at their opposite ends. Through these apertures are passed bolts, or the like, employed for supporting heavy wooden runners 34. This type of post and fence construction is especially adapted for highway service to protect traffic from turns and gullies or ditches along the side of the same.

It is to be understood that the forms of this invention shown herein and described are preferred. However, various changes in the shape, size and arrangement of parts may be made without departing from the spirit of the invention or the scope of the subjoined claims.

I claim as my invention:

1. A post, comprising a rectangular base portion, a triangular portion extending perpendicularly of the base, and a reduced extension projecting from the triangular portion; one wall of each of the base portion, the triangular portion and the extension coinciding in a vertical plane, reenforcing means extending through the base portion, triangular portion and reduced extension and arranged in parallelism with the aforesaid coinciding walls, and a reenforcing element extending through the remaining parts of the triangular portion and base portion and arranged substantially in parallelism with the hypotenuse of the triangular portion, said reenforcing members being independent of each other and each formed in a continuous spiral throughout its length.

2. A post including three portions of substantially equal height and comprising a rectangular base portion, a triangular portion located above the base portion and a reduced extension projecting perpendicularly of the last mentioned portion, a set of reenforcing members extending through all of said portions, and a second set of reenforcing members extending through the base and triangular portions and arranged at an angle to the first set of members.

In testimony whereof I affix my signature.

ATLAS M. THOMPSON.
